CLAIM

The ornamental design for the remote for rechargeable RGB LED light, as shown and described.

DESCRIPTION

FIG. 1 is a front perspective view of the remote for rechargeable RGB LED light, showing my new design;

FIG. 2 is a rear perspective view of the remote for rechargeable RGB LED light thereof;

FIG. 3 is a front view of the remote for rechargeable RGB LED light thereof;

FIG. 4 is a rear view of the remote for rechargeable RGB LED light thereof;

FIG. 5 is a left side view of the remote for rechargeable RGB LED light thereof; and,

FIG. 6 is a top view of the remote for rechargeable RGB LED light.

The broken lines in the figures illustrate portions of the remote for rechargeable RGB LED light that form no part of the claimed design.

1 Claim, 6 Drawing Sheets
